No. 893,054.

PATENTED JULY 14, 1908.

M. M. CONDRON.

WRENCH.

APPLICATION FILED JUNE 26, 1907.

UNITED STATES PATENT OFFICE.

MARK M. CONDRON, OF MARSHFIELD, OREGON.

WRENCH.

No. 893,054.

Specification of Letters Patent.

Patented July 14, 1908.

Application filed June 25, 1907. Serial No. 380,700.

To all whom it may concern:

Be it known that I, MARK M. CONDRON, a citizen of the United States, residing at Marshfield, in the county of Coos and State 5 of Oregon, have invented a new and useful Wrench, of which the following is a specification.

This invention relates to wrenches and its object is to provide a wrench which can be 10 quickly adjusted to nuts of different sizes and tightly grip them.

Another object is to provide a wrench the adjustable jaw of which is designed to positively engage the shank when in locked position, the mechanism for locking the jaw being of simple, durable and efficient construction.

With these and other objects in view the invention consists of certain novel features 20 of construction and combinations of parts which will be hereinafter more fully described and pointed out in the claims.

In the accompanying drawings is shown the preferred form of the invention.

25 In said drawings: Figure 1 is a side elevation of a wrench constructed in accordance with the present invention, portions of the slidable jaw being broken away. Fig. 2 is a front view of a portion of the shank and of 30 the jaws thereon, the adjustable jaw being shown partly in section. Fig. 3 is a section on line $x-x$, Fig. 1. Fig. 4 is a section through a portion of the adjustable jaw, said section being taken on the line $y-y$, Fig. 3, 35 and showing the locking block disengaged from the shank. Fig. 5 is a view similar to Fig. 4 and showing the shank engaged by the locking block. Fig. 6 is a longitudinal section through the adjustable jaw, the locking 40 mechanism being removed therefrom. Fig. 7 is an elevation of a portion of one side of the adjustable jaw. Fig. 8 is an elevation of a portion of the other side of the adjusting 45 jaw. Fig. 9 is a view of the adjusting device of the locking block, the parts of said device being detached and shown in perspective.

Referring to the figures by characters of reference, 1 designates a shank having a handle 2 secured to one end thereof in any preferred manner, while the other end of the shank has a fixed jaw 3 secured thereto or formed therewith. One face of the shank is provided with rack teeth 4 for the purpose hereinafter set forth. Mounted upon the 55 shank is an adjustable jaw 5 having a passage 6 extending therethrough and in which

the shank 1 is disposed. Formed within the jaw 5 and opening into the passage 6 is a rectangular recess 7, one side wall of which is provided with a small oval or elliptical aperture 8 while the opposite wall has a larger similar opening 9. Fitting within the recess 7 is a locking block 10 which is held against lateral movement by the walls of the recess but is free to move in the direction of its 60 length or toward or from the shank 1. This block is provided upon one face with teeth 11 designed to engage the teeth upon the shank and a circular opening 12 extends through the central portion of the block. The outer 65 face of the block is inclined inwardly from the center thereof so as to form an angle 13 against which bears a spring 14 suitably secured within a groove 15 formed in jaw 5 adjacent the recess 7. Revolubly mounted 70 within the opening 12 is an eccentric 16 at one end of which is disposed a large circular head 17 designed to rotate within the opening 9 while at its other end is a small circular head 18 designed to rotate within the opening 80 8. These two heads are concentric and projecting from the small head 18 is an angular projection 19 designed to project into a lever 20 and to be held in engagement therewith by means of a retaining screw 21. A cam 22 85 extends from the periphery of the head 17 and a corresponding cam 23 is located on one face of the lever 20. These cams are designed to travel upon the side faces of the jaw 5 and are movable upon a pair of fixed 90 stop lugs or projections 24 formed upon the sides of the jaw 5.

The spring 14 serves to hold the block 10 normally in engagement with the shank. When, however, it is desired to disengage the 95 block from the shank so as to permit the movable jaw to slide along the shank, lever 20 is swung in one direction so that the cams 22 and 23 will ride upon lugs 24. The cams will therefore shift the eccentrics longitudinally within the openings 8 and 9 and cause the block 10 to move out of engagement with the teeth. By swinging the lever in the other direction the cams will not ride upon the lugs and therefore the block 10 will be 100 maintained in engagement with shank 1, the heads 17 and 18, however, acting as eccentrics to push the jaw 5 forward toward the fixed jaw and therefore it becomes possible to 105 secure a very minute adjustment for the purpose of permitting the jaws to tightly clamp upon any nut which may be placed be-

tween them: The lever can be easily manipulated by the thumb of the hand grasping the wrench.

It will be seen that the parts can be readily assembled, the eccentric being insertible into position through the large opening 9 and the screw 21 constituting means for holding the lever as well as the eccentric in proper position.

10 Importance is attached to the wrench herein described because of its simplicity and strength, its inexpensive construction, and the ease with which it may be operated.

What is claimed is:

15 1. In a wrench the combination with a shank; of a jaw slidably mounted upon the shank, a shank engaging member movable within the slidable jaw, yieldable means for holding said member and the shank normally in engagement, and an eccentric revolvably mounted within the movable jaw and the member therein and disposed when rotated to positively shift the slidable jaw in either direction in relation to the member 25 therein.

20 2. In a wrench the combination with a shank; of a jaw slidably mounted upon the shank, a shank engaging member movably mounted within the slidable jaw, a revolute 30 element within said member and shiftable within the slidable jaw, and means operated

by said element for shifting said element to move the shank engaging member out of engagement with the shank.

3. In a wrench the combination with a shank; of a jaw slidable upon the shank, a member movably mounted within the jaw, yieldable means for holding said member normally in engagement with the shank, a revoluble element within said member and 40 shiftable therewith within the jaw, lifting cams movable with said element, and stop devices upon the slidable jaw and co-operating with said lifting cams for disengaging the movable member from the shank.

4. In a wrench the combination with a toothed shank; of a jaw slidably mounted thereon, a spring pressed member movably mounted within the jaw and normally engaging the shank, a lifting cam revolvably 50 mounted upon said member, a stop device upon the jaw and in the path of said cam, and means for moving the cam against the stop device to shift said member from engagement with the shank.

In testimony that I claim the foregoing as my own, I have hereto affixed my signature in the presence of two witnesses.

MARK M. CONDRON.

Witnesses:

J. E. COWAN,
B. J. HIGGINS.
